UNITED STATES PATENT OFFICE.

LEONHARD KELLENBERGER, OF ST. GALLEN, SWITZERLAND.

MANDREL-PRESS.

1,393,789.

Specification of Letters Patent.

Patented Oct. 18, 1921.

Application filed April 17, 1920. Serial No. 374,673.

To all whom it may concern:

Be it known that I, LEONHARD KELLENBERGER, a citizen of the Republic of Switzerland, residing at St. Gallen, in the Canton 5 of St. Gallen, Switzerland, have invented certain new and useful Improvements in Mandrel-Presses, of which the following is a specification.

This invention has reference to mandrel-10 presses and is distinguished from known devices of this kind in that it possesses the advantage of being adapted to be used as a jack-and-pinion-press for small down-pres-15 sures and also as a spindle-press for heavier down-pressures. The apparatus according 20 to this invention is moreover adapted for use as an anvil block and has the further advantage that, with the aid of and when used as a jack-and-pinion-press, it allows of quick adjustment of the latter in relation to 25 the working piece whereupon, by the application of the device as a spindle-press, any required greater pressure can be exerted and thus much time saved.

25 The accompanying drawing illustrates the invention by way of example, both Figure 1 and Fig. 2 showing an elevation of the de- 30 vice, the position of certain parts of the lat- 35 ter figure being, however, varied. Fig. 3 represents a vertical section through Fig. 1.

In carrying out this invention I make pro- 35 vision of a press frame or stand *a* which at the front, at *b*, is formed with a base plate. Adjacent to this base plate is a second plate 40 *m* serving as a rest for the working piece into or from which the mandrel is pressed or withdrawn respectively. *c* designates a rack which, instead of cylindrical form as shown, may of course also be of square or other 45 section. This rack is slidably mounted in a sleeve *d* provided with external screw-threads, and the said sleeve is fashioned at its upper end into a head *e* serving to receive the pinion *f* engaging with the teeth 50 of the rack *c*. The sleeve *d* is screwed into the correspondingly screw-threaded top portion of the frame *a* and so arranged that it can be easily adjusted in a vertical direction. By means of a bolt *h*, which is adapted to 55 be fixed into a drilled extension *i* of the frame *a* and to abut against the head *e* of the sleeve, the latter can, if desired, be safeguarded against turning. The turning of the pinion *f* is effected by a lever *g* so that 55 the rack *c*, serving at the same time as a

driving or pressing means is moved downward against the mandrel and working piece (shown in chain-dotted lines, Fig. 1).

If, however, it is desired instead of the rack to employ and utilize the spindle feed 60 of the sleeve *d*, the safety bolt *h* is removed from its position shown in Fig. 1 and placed into an opening *k* provided in the head *e* of the sleeve. The lever *g* is thereby se- 65 cured in a horizontal position, Fig. 2, and the sleeve *d* is made free to be rotated. That is to say, the rack is now blocked from movement while the screw-threaded sleeve is 70 adapted to be used as a press with a corre- 75 spondingly more powerful down-pressure. 70

The base plate *b* has a longitudinally dis- 75 posed recess in order to receive two prismatical members *l* which, as illustrated in Fig. 2, serve as rests for a shaft *y* or the like when it is desired to utilize the apparatus as an 80 anvil block. Thus, if the shaft *y* is not rectilineal, it is merely necessary to slide the two prismatical members *l* within the recess in the base plate *b* and bring them to near a point of the shaft where pressure is to be 85 applied. Subsequent to the adjustment of the shaft *y* into the position shown in Fig. 2 and its straightening by means of the press, the said shaft may be fixed between the ad- 90 justable points *o* of a centering device and 95 tested as to its roundness and true running. The centering device may be of any suitable and known construction. However, in the present case the rod *n* carrying the adjustable points *o* is arranged at the rear of the frame 90 *a* in order that provision may be made at the front of the base plate *b* of the necessary open- 95 ing *p* for the reception of the corresponding end of the mandrel when the latter is pressed into the working piece or when the mandrel is removed therefrom.

Another improvement consists of the ar- 100 rangement of two struts *q* pivoted to the front of the base plate *b* and adapted to en- 105 gage a pin *r* secured near the top of the frame *a*, the purpose being to relieve the said frame of the strain, that is, of the moment of flex- 110 ion. If the working piece is of compara- 115 tively large size as indicated at *x* in Fig. 1, the two struts *q* must be disengaged from the pin *r*, this being quickly and easily effected.

It will be understood that instead of mounting the rack within the sleeve, the construction could be reversed in such a manner that the said sleeve is caused to move 110

in the rack. Such a modification would not alter the character of this invention.

Having now fully described my said invention what I claim and desire to secure 5 by Letters Patent is:—

1. In an improved mandrel-press, the combination with a stand having a base plate, of a screw-threaded sleeve adjustably screwed into the top portion of the stand, a 10 rack slidably mounted within the sleeve, means to operate the said rack when small down-pressure is required, and means to block the rack from movement and cause the said sleeve to be independently moved 15 for use with heavy down-pressure.

2. In the herein described mandrel-press, the combination with a stand having a base plate, of a screw-threaded sleeve adjustably screwed into the top portion of the stand 20 and having an integral extended head, a rack mounted within the said sleeve, a pinion journaled in the head part of the sleeve and engaging with the teeth of the rack, and a lever connected to the pinion, the said lever, 25 when turned about a horizontal axis causing the rack and pinion to be operated, and when turned about a vertical axis, being adapted to move the aforesaid sleeve, substantially as and for the purpose set forth.

30 3. In the herein described mandrel-press, the combination with a stand, of a screw-threaded sleeve adjustably screwed into the

top portion of the stand and having an integral extended head provided with an opening, a rack journaled in the said sleeve, a pinion rotatably mounted in the head part 35 of the sleeve and engaging with the teeth of the rack, means to actuate the pinion and the rack, and means for blocking the movement of the said sleeve and the rack and pinion respectively, the said means for blocking these movements comprising a bolt adapted, respectively, to be fixed in the extended top part of the stand and abut against the head of the sleeve, and be removed and inserted into the aforesaid opening in the extension of the sleeve, all substantially as set forth and shown.

4. In a mandrel-press of the type described, the combination with a stand having a pin attached near its top end, of a base plate integral with the stand, and struts pivoted to the said base plate and adapted to be brought into engagement with and out of engagement from the said pin, 50 substantially as and for the purpose set forth.

In testimony whereof I have hereunto set my hand in the presence of two subscribing witnesses.

LEONHARD KELLENBERGER.
